UNITED STATES PATENT OFFICE.

FRED H. LOVELESS, OF LAFAYETTE, INDIANA, ASSIGNOR OF TWO-THIRDS
TO GEORGE C. ZELLER AND GEORGE J. LANGE, OF SAME PLACE.

DESIGN FOR A BRUSH-BACK.

SPECIFICATION forming part of Design No. 29,613, dated November 8, 1898.

Application filed September 6, 1898. Serial No. 690,337. Term of patent 7 years.

To all whom it may concern:

Be it known that I, FRED H. LOVELESS, a citizen of the United States, residing at Lafayette, in the county of Tippecanoe and State 5 of Indiana, have invented and produced a certain new and useful Design for a Brush-Back, of which the following is a specification.

My new design is illustrated by the accompanying drawings, in which—

10 Figure 1 is a top or plan view of my brush-back; Fig. 2, the same in side elevation, and Fig. 3 a longitudinal section on the dotted line 3 3 of Fig. 1.

The leading features of this design for a 15 brush-back consist in a four-sided central part with approximately parallel sides, but having the corners rounded off to present circular outlines for the flat surfaces, especially of the sides and top. On two opposite sides 20 of this central portion are half-spherical extensions with their widest or base parts next to the above-mentioned central part. The requisite length of the brush-back is obtained by duplicating the spherical extensions, the 25 entire system on both sides of the four-sided center block being on a common axis and all of the spherical parts being practically of the same diameter. These spherical parts are connected by necks of reversed curvature in 30 contour, the radius of curvature being the

same as that of the spheres. The under side of the brush-back is straight, except at the ends, which turn up slightly, and at equal intervals along this under side a series of sockets are formed. There is, in fact, one socket to 35 each one of the spherical and hemispherical parts.

A represents the middle part with the four flat sides a , and A' are the rounded corners, which give the sides a a rounded or circular 40 outline.

B are the two hemispherical extensions, and C are the spherical extensions from the parts B.

D are the necks, of reversed curvature from 45 d to d' .

The straight under side E is turned up at the ends from e to e' , and F are the sockets above mentioned.

What I claim is—

50 The design for a brush-back substantially as shown and described.

In witness whereof I have hereunto set my hand and seal, at Indianapolis, Indiana, this 29th day of August, A. D. 1898.

FRED H. LOVELESS. [L. S.]
